US00D710345S

(12) **United States Design Patent**
Chang

(10) **Patent No.:** **US D710,345 S**
(45) **Date of Patent:** **** Aug. 5, 2014**

(54) **PROTECTIVE COVER**

(71) Applicant: **David Chang**, Houston, TX (US)
(72) Inventor: **David Chang**, Houston, TX (US)
(**) Term: **14 Years**
(21) Appl. No.: **29/453,334**
(22) Filed: **Apr. 26, 2013**
(51) LOC (10) Cl. **14-03**
(52) U.S. Cl. **USPC D14/250**

(58) **Field of Classification Search**

(57) **CLAIM**

The ornamental design for a protective cover, as shown and described.

DESCRIPTION

FIG. 1 is a perspective view of a protective cover showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the protective cover shown housing a smart phone.

The features of the various figures shown in broken lines depict environmental subject matter only, which forms no part of the claimed design.

1 Claim, 4 Drawing Sheets
